UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

1,271,718.

Specification of Letters Patent.

Patented July 9, 1918.

Application filed September 28, 1915. Serial No. 53,000.

To all whom it may concern:

Be it known that I, DAVID S. KENNEDY, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such for instance as the linotype machine disclosed in U. S. Letters Patent to J. R. Rogers, Nos. 848,771 and 930,693, wherein matrices of different styles or fonts 15 are stored in a series of superposed magazines and are delivered from one or another thereof at will, in order that a line may be produced with the face represented by the matrices in any one magazine, or with a 20 combination of faces represented by matrices in two or more magazines; and wherein there is employed a movable throat or switch and a series of escapement actuating devices shiftable into operative relation to any selected magazine so as to deliver the matrices 25 therefrom to a common assembling mechanism.

In machines of the kind specified, the throat and escapement actuating devices are 30 shifted from one magazine to another by hand, requiring considerable time and effort. To obviate this disadvantage, I have provided improved power-driven means under the control of finger key mechanism for effecting the shifting or adjusting operations 35 described, so that a change from one magazine to another may be effected by the mere depression of a key, thus insuring greater speed in the operation of the machine and 40 relieving the operator of all manual effort. These and other improvements will be fully described in the detailed description to follow and finally pointed out in the claims.

In the accompanying drawings, I have 45 shown my invention merely in preferred form and by way of example and as applied to the particular style of machine mentioned, but obviously many changes and variations may be made therein and in its mode of application, which will still be comprised within its spirit. Thus, it may be applied to other forms of typographical machines, such as typesetters and the like, which handle type or dies instead of matrices. Gener- 50 ally speaking, I desire it to be understood

that I do not limit myself to any specific form or embodiment, except in so far as such limitations are specified in the claim.

Referring to the drawings:

Figure 1 is a side elevation of a portion 60 of a linotype machine having my invention applied thereto;

Figs. 2, 3, 4 and 5 are vertical sections, partly broken away, showing the parts in different relative positions; 65

Fig. 6 is an end elevation of the parts shown in Fig. 2;

Fig. 7 is a side elevation of the upper portion of the machine showing the magazines; 70

Fig. 8 is a similar view showing the magazines in separated condition for removal;

Fig. 9 is a section on the line 9—9 of Fig. 7;

Fig. 10 is a section on the line 10—10 of 75 Fig. 2;

Figs. 11, 12, 13 and 14 are detail views of the holding and locking devices for the escapement supporting frame;

Fig. 15 is a perspective showing certain 80 details;

Figs. 16 and 17 are details of the driving clutch in different positions; and

Figs. 18 and 19 are end views, partly broken away, of the parts shown in Figs. 16 85 and 17 respectively, looking from the right.

As in the Rogers patents previously mentioned, the matrices are stored in a plurality of superposed magazines A and are controlled in their release therefrom by escapements B¹ of the usual construction. For purposes of illustration, only two magazines are shown herein, but the number may be increased to any desired extent. The escapements of the magazine in operation are 90 actuated through the medium of the small pivoted levers B² by the vertical slides or members B³ formed with the rows of notches B⁴, in one or another of which rows engage the free ends of the pivoted operating levers 100 B⁵ controlled in the usual way from the keyboard mechanism through the reeds B⁶. As the matrices are released from the magazines, they pass downward through the throat or switch C into the vertical channeled raceway C¹, by which they are delivered to the other assembling devices. The throat C and the escapement actuating members B³ are carried by the vertically movable supporting frame D so as to be shiftable 105 110

into operative relation to any selected one of the magazines, the supporting frame D having tongues D¹ (Fig. 10) slidably engaged in guideways C⁴ of the framework C² 5 of the raceway C¹.

In accordance with my invention, the vertical movements of the supporting frame D are effected by power-driven means under the control of finger key mechanism, as now 10 to be described. The frame D is formed at its opposite ends (Figs. 10 and 15) with guideways D⁵ wherein are arranged vertical slides F provided at their lower ends with lifting blocks or shoulders F⁴ to engage the 15 frame, and formed with rearwardly extending arms F⁶ having studs or rollers F³ which engage in the forked or slotted ends H¹ of a pair of arms H fast upon a transverse rock shaft H² suitably journaled in the 20 machine frame. The shaft H² is provided at one end with a further arm H³, connected by a link H⁴ to a vertical slide H⁵ suitably guided in the machine frame, and provided at its lower end with a roller H⁶ engaging 25 in a cam groove H⁷ of a rotary cam H⁸, whereby the frame D, through the intermediate connections described, may be elevated or lowered to register the parts with the selected magazine.

30 The escapement actuating members B³ are movably arranged in a supplemental sash-frame E, which is supported in the frame D (Figs. 10 and 15) by pairs of studs or rollers E² projecting from its opposite ends 35 and engaging in transverse elongated slots D² of the frame D. As thus supported, the frame E may be moved laterally or backward and forward relatively to the frame D so as to make or break the connection of the 40 actuating members B³ with the pivoted levers B⁶ and to locate the actuating members beneath or clear of the small escapement levers B². This movement of the frame E is controlled by the slides F, before referred to, they being formed on their 45 front edges with inclined or cam surfaces F¹ which are arranged to engage extended portions of the rollers E² of the frame and push the latter forwardly against the action 50 of springs E¹ tending to shift and hold it in its rearward position. The parts are so arranged that when the slides F are shifted upwardly, their cam surfaces F¹ push the frame E forwardly before the 55 shoulders F⁴ become engaged with the frame D, as shown in Fig. 3, so that the position of the latter is not disturbed until the escapement actuating members B³ are drawn forwardly out of engagement with the levers B⁵ and clear of the levers B². The continued movement of the slides F then brings the shoulders F⁴ in engagement with the frame D, as shown in Fig. 4, and causes it to be shifted upward therewith.

60 65 In order to support the frame D in its

uppermost position and with its connected parts in the exact location required, there is provided a pair of spring-actuated dogs J pivoted at their lower ends, as at J¹, to rearwardly projecting arms C⁶ of the front 70 framework C² and formed at their upper ends with flat surfaces or shoulders J² to engage beneath blocks D⁴ attached to the opposite ends of the frame. The blocks D⁴ are formed with beveled surfaces D^a to co-operate with corresponding bevel surfaces J³ on the dogs J so as to throw them rearwardly during the upward movement of the frame. When, however, the blocks D⁴ pass beyond the dogs, the latter are immediately 75 snapped back into operative position by their springs so as to engage beneath the blocks D⁴ and give rigid support to the frame. After the frame D has been raised to and supported in its upper position, the 80 escapement actuating members B³ should be returned to their normal or rearmost position; and for this reason, the slides F are allowed to recede slightly relatively to the frame D when the latter comes to rest on 85 the dogs J, thus permitting the springs E¹ to press the frame E rearwardly and bring the actuating members in operative relation to the levers B² and also effect their re-engagement with the operating levers B⁶. 90

In order to avoid any tendency of the slides F to raise the frame D before the escapement actuating members B³ have been shifted forwardly, there is provided a pair of spring-actuated hooks G pivoted to the 100 framework C² and arranged in engagement with pins D³ of the frame D when the latter is in its lowermost position, as shown clearly in Fig. 6. The engagement and disengagement of the hooks G is controlled automatically by the raising and lowering of the frame D, the blocks F⁴ of the slides F being formed with bevel surfaces F⁶ to co-operate with corresponding bevel surfaces G¹ on the hooks, and the parts being so arranged that 110 the disengagement of the hooks is effected before the blocks F⁴ come into engagement with the frame D to lift it.

The foregoing shifting of the parts, from the lower magazine to the upper one, is effected by a half rotation of the cam H⁸, its groove H⁷ being so shaped and proportioned as to carry out the movements in the sequence described. Thus, as indicated by dotted lines in Fig. 2, the shape of the cam 115 is such that during its rotation for the first forty-five degrees the slides F are raised sufficiently relatively to the frame D to carry the frame E to its foremost position, as shown in Fig. 3; that during its rotation 120 for the next fifteen degrees, the slides are lifted slightly further to disengage the hooks G from the pins D³ of the frame D and immediately thereafter bring the shoulders F⁴ into engagement with the frame D; 125 130

that during its rotation for the next seventy-five degrees, the slides F are raised still further to shift the frame D upwardly to a point just beyond its final position, as indicated in Fig. 4; and finally that during the last forty-five degrees of its rotation, the slides F are pulled downwardly to a slight extent to allow the frame D to settle on the sustaining hooks J (which had previously been pushed out of the way) and by their continued relative movement to permit the springs E¹ to press the frame E rearwardly to its original and normal position, as illustrated in Fig. 5.

When the parts are shifted in the opposite direction, that is, from the upper magazine to the lower one, the other half of the cam groove is active, as shown by dotted lines in Fig. 5; and its shape is such that during the initial rotation of the cam, the slides F are shifted upwardly to a slight extent to withdraw the frame E in the manner before described and to bring their sustaining shoulders F⁴ into engagement with the frame D, and then the slides are carried downwardly to locate the frame D in its lower position, it being arrested in such position before the slides have completed their downward movement, with the result that the continued relative movement of the slides allows the springs E¹ to press the frame E rearwardly to its normal position. To permit the downward movement of the frame D, however, it is necessary that the sustaining dogs J be removed from the path of the blocks D⁴, and this is effected by the engagement of inclined projections H¹¹ on the inner sides of the arms H with spring-pressed pawls J⁴ pivoted to the rear edges of the dogs and having stops which allow them to yield only in a forward direction. When the arms H are swung upwardly to raise the slides F preparatory to the downward movement of the frame D, the projections H¹¹ engage the rear faces of the pawls, and press them forwardly out of the way. After the projections have passed, however, the pawls are immediately returned by their springs to their original position, so that upon the downward movement of the arms H, the projections pass in front of the pawls, and due to the engagement of their stops with the dogs J, the latter are rocked rearwardly out of the path of movement of the blocks D⁴.

The half rotations of the cam H⁸ above described are effected by power-driven means under the control of a finger key and in such manner that the repeated actuations of the key cause the assembling devices to be shifted back and forth between the two magazines alternately. Referring to Figs. 1 and 10, it will be seen that the cam H⁸ is fast upon a short shaft or stud H⁹ suitably journaled in the framework and provided

alongside the cam with a large gear H¹⁰ meshing with a smaller gear K secured to a clutch sleeve K¹ loose upon a driving shaft K², which has fast thereon a further gear K³ meshing with a gear L¹ on the constantly rotating "intermediate" shaft L (see also Figs. 16 to 19). The sleeve K¹ is provided at one end with teeth K⁴ adapted to interlock with corresponding teeth on the boss of the gear K³ so as to establish an operative connection between the driving shaft and the cam H⁸. Normally, however, this connection is broken through the action of a spring K⁵ inclosed within the sleeve K¹ and tending constantly to hold its teeth out of engagement with those of the gear K³. The action of the spring may be overcome by a pivoted lever K⁶ connected by a link K⁷ to a pivoted key or key lever K¹¹, the arrangement being such that the depression of the key shifts the sleeve K¹ axially along the shaft K² to effect its connection with the gear K³ in the manner just described. When the sleeve K¹ is thus connected, the motion of the shaft K² is imparted to the cam H⁸, whose rotation locates the assembling devices in operative relation to one or another of the magazines.

The parts are so proportioned that one complete rotation of the shaft K² effects a one-half rotation of the cam H⁸, and since the cam is intended to make such partial rotation only at each actuation of the key K¹¹, devices are provided to break the driving connection when the shaft K² makes its complete rotation. To this end, the clutch sleeve K¹ is provided with a disk K⁸ arranged to coöperate with a roller K¹⁰ journaled to a bracket K¹² on the machine frame. The disk K⁸ is formed in its periphery with a notch K⁹ wherein the roller K¹⁰ normally engages, i. e., when the sleeve is disconnected from the gear K³. When, however, the sleeve is shifted axially into engagement with the gear, the disk is carried therewith and located beyond the roller K¹⁰, so that when the sleeve begins to rotate, the notch K⁹ is moved out of registry with the roller, which then bears against the rear face of the disk and holds the sleeve in engagement with the gear against the action of the spring K⁵ until the notch again comes into registry with the roller, when the spring is allowed to break the connection and permit the parts to come to rest. At this time, the shaft K² has made a complete rotation and consequently has imparted a half rotation to the cam H⁸, which in turn has shifted the assembling devices into operative relation to one or the other of the magazines, according to which half of the cam groove H⁷ was active at the time. The present invention also contemplates an improved arrangement of the magazines A and their escapements B¹. Referring to

Figs. 7, 8 and 9, it will be noted that the magazines are mounted upon the customary base frames A^1 which, in the present instance, are pivotally connected at their upper ends, as at A^2 , to the machine frame, and at their lower ends rest upon and are supported by set screws A^3 projecting upwardly from the machine frame. According to this arrangement, the magazines and their base frames are independently supported and are capable of being rocked upwardly about the pivots A^2 . This upward rocking of the magazines is effected by means of two pairs of cams M and M^1 , the former arranged to coöperate with surfaces A^5 on the under base frame, and the latter with lugs A^4 projecting forwardly from the upper base frame. Both pairs of cams are fast upon a transverse rock shaft M^2 which is suitably journaled in the machine frame and provided at one end with an operating handle M^3 , whereby the cams are rotated in unison. For reasons which will presently appear, the cams of the two pairs are formed so as to swing their corresponding magazines upwardly to different extents.

The escapements B^1 for each magazine and their actuating levers B^2 are mounted in a supporting frame B , which is pivotally connected, as at B^a , to the corresponding base frame A^1 so as to be movable downwardly away from the magazine to disengage the escapements therefrom and to permit its independent removal. Such swinging of the escapement frames is permitted by the upward movement of the magazines just described, it being noted that due to the differential throw of the cams M and M^1 the two magazines are sufficiently separated to allow the escapements for the upper magazine to be swung downward without interference with the lower one, as clearly shown in Fig. 8.

When the escapements are thus disengaged from the magazines, it is obvious that the matrices therein contained would be free to pass therefrom unless otherwise locked. Devices are therefore provided which will prevent the disengagement of the escapements from the magazines until the matrices have first been locked therein. In the present instance, each of the escapement supporting frames B is held in operative relation to its corresponding magazine by means of a latch N^2 carried by an arm N pivotally connected, as at N^1 , to the supporting frame. By rocking the arm N about its pivot N^1 , therefore, the latch N^2 may be engaged with or disengaged from the magazine at will, the arm N being provided at its lower end and below its pivot with a projecting nose N^5 to limit the extent of its outward movement. In order to permit the ready engagement and disengagement of the latch N^2 , it is pivotally

connected, as at N^3 , to the upper end of the arm N , being held in its active position by a spring N^4 seated in a recess in the arm N and bearing against the outer end of the latch N^2 , as clearly shown in Fig. 11. The premature disengagement of the latch N^2 is prevented by a sliding plate N^6 having its rear end N^7 bent laterally and forwardly so as to engage behind the outer face of the arm N . The plate N^6 is arranged to slide forwardly and backwardly to lock or unlock the arm N , it being mounted in a fixed arm N^8 projecting upwardly from the escapement frame B and held normally in its locking position by a spring N^9 arranged between its laterally bent portion N^7 and an upstanding arm N^{10} on the escapement frame. The plate N^6 is adapted to be controlled by the customary matrix locking bar O (see Fig. 8) which is inserted through the opening A^7 (Fig. 11) in the edge of the magazine, the bar being formed with a bevel surface so that as it is thrust into the magazine the plate N^6 will be pushed rearwardly thereby to release the arm N and permit the latter to be swung outwardly to disengage the latch N^2 from the magazine, as indicated by the dotted lines in Fig. 13, and thus to permit the escapement frame B to be lowered away from the magazine. It will be understood that the holding and locking devices attached to the escapement frame B will preferably be arranged at both edges of the magazine.

In the present instance, the magazines A have their lower ends straight or rectangular (which is the form in most general use) and out of alignment with each other, so that it becomes necessary to provide for the delivery of the matrices therefrom into the shiftable throat C , which, as before described, is arranged to move vertically in a straight path from one to another of the magazines. To this end, there is provided for each magazine a short channeled section A^6 having its partitions adapted to register with the partitions of the throat C so as to guide the matrices in the proper manner from one to the other. The sections A^6 have their lower ends beveled or inclined and located in a vertical plane corresponding to the path of movement of the throat C , so that the latter may be shifted directly into operative relation to one or the other. The sections A^6 are supported by the swinging escapement frames B so as to be movable out of the path of the magazines when the latter are to be moved from the machine.

To permit the removal of the magazine, the assembling devices are as usual carried by the supporting frame C^2 , which is arranged to be swung forwardly about the vertical pivot C^3 (Fig. 10). It is pointed out that, in addition to the ordinary as-

sembling devices, the slides F, the hooks G and the dogs J¹ are also carried by the frame so as to be movable therewith, the slots H¹ of the arms H permitting the latter 5 to be automatically connected with and disconnected from the slides F as the frame is moved to and from its operative position. In other words, the connections between the power driven means and the movable 10 assembling frame D are such as to be made and broken automatically as the supporting frame C² is moved to and from its operative position.

As previously stated, I have shown my 15 improvements merely in preferred form and by way of example and as applied to the particular kind of machine described, but it will be obvious that many modifications and alterations will readily suggest themselves 20 to those skilled in the art without departing from the scope of the invention.

Having thus described my invention, its 25 construction and mode of operation, what I claim and desire to secure by Letters Patent of the United States is as follows:

1. In a typographical machine, the combination of a plurality of magazines each having a series of escapements, a series of actuating members therefor, a supporting 30 frame for the actuating members, mechanism for moving the supporting frame to locate the actuating members in operative relation to one or another of the magazines, including a longitudinally movable device 35 through which the frame is moved, and means controlled by said device to shift the actuating members out of operative relation to the escapements before the movement of the frame.

40 2. In a typographical machine, the combination of a plurality of superposed magazines each having a series of escapements, a series of actuating members therefor, a supporting frame movable from one magazine 45 to another, a supplemental frame carrying the escapement actuating members and mounted in the supporting frame so as to be shiftable forwardly and backwardly therein, mechanism for raising and lowering 50 the supporting frame, including a vertically movable device to engage said frame, and means controlled by said device for shifting the supplemental frame forwardly and backwardly relatively to the supporting 55 frame before and after the latter's movement, respectively.

3. In a typographical machine, the combination of a series of escapement actuating members, a movable supporting frame, a 60 supplement frame carrying the actuating members and mounted in the supporting frame so as to be shiftable laterally relatively thereto, mechanism for moving the supporting frame to different operative positions, means actuated by the initial opera-

tion of said mechanism for effecting the shifting of the supplemental frame, and locking devices to prevent the movement of the supporting frame during the relative shifting of the supplemental frame. 70

4. In a typographical machine, the combination of a series of escapement actuating members, a movable supporting frame, a supplemental frame carrying the actuating members and mounted in the supporting 75 frame so as to be shiftable laterally relatively thereto, mechanism for moving the supporting frame to different operative positions, means actuated by the initial operation of said mechanism for effecting the shifting of the supplemental frame, locking devices to prevent the movement of the supporting frame during the relative shifting of the supplemental frame, and automatic means for disengaging the locking devices 80 after the relative shifting of the supplemental frame so as to permit the movement of the supporting frame. 85

5. In a typographical machine, the combination of a plurality of magazines each 90 having a series of escapements, a series of actuating members for the escapements, a supporting frame movably arranged so as to locate the actuating members in operative relation to the escapements of one or another of the magazines, mechanism for effecting such movement of the supporting frame, and locking devices, adapted to be released by the initial operation of said mechanism, for holding the supporting 95 frame against movement. 100

6. In a typographical machine, the combination of the movable frame D, the vertical slides F for raising and lowering it, the supplemental frame E carrying the 105 escapement actuating members B², and mounted in the frame D so as to be shiftable forwardly and backwardly therein by the slides F, and the hooks G, adapted to be disengaged by the slides F, for holding 110 the frame D against upward movement.

7. In a typographical machine, the combination of a plurality of magazines, assembling devices, a supporting frame therefor, mechanism for raising and lowering the 115 frame to locate the assembling devices in operative relation to one or another of the magazines, and means distinct from said mechanism and mounted independently of the supporting frame for holding it in its raised position, said means being controlled automatically by the movement of the frame. 120

8. In a typographical machine, the combination of the assembling devices, a supporting frame therefor, mechanism for raising and lowering the frame, a sustaining dog mounted independently of the frame for holding it in its raised position, and automatic means for controlling the action of the dog when the supporting frame is moved. 130

9. In a typographical machine, the combination of the assembling devices, a supporting frame therefor, mechanism for raising and lowering the frame, a sustaining dog pivotally mounted upon a relatively fixed part of the machine to engage and hold the supporting frame in its raised position, and automatic means for disengaging the dog when the frame is lowered.
10. In a typographical machine, the combination of the assembling devices, a supporting frame therefor, mechanism for raising and lowering the frame, a sustaining dog mounted independently of the frame to engage and hold it in its raised position, and devices distinct from and controlled by said mechanism to disengage the dog when the frame is lowered.
11. In a typographical machine, the combination of the vertically movable frame D, mechanism for raising and lowering the frame, and the spring actuated sustaining dog J mounted independently of and adapted to engage and hold the frame in its raised position independently of said mechanism, the said dog being controlled automatically by the movement of the frame.
12. In a typographical machine, the combination of the vertically movable frame D provided with the shoulders D⁴, mechanism for raising and lowering the frame, and the spring-actuated sustaining dogs J having shoulders J² to engage beneath the shoulders D⁴ and hold the frame in its raised position independently of the raising and lowering mechanism.
13. In a typographical machine, the combination of the movable frame D, the relatively shiftable frame E supported therein and having the projecting studs E², and mechanism for moving the frame D, the said mechanism including the vertical slides F having the inclined surfaces F¹ coöoperating with the studs E².
14. In a typographical machine the combination of the movable frame D, the supplemental frame E supported thereby and shiftable backwardly and forwardly therein, and mechanism for raising and lowering the frame D, including the vertical slides F formed with the lifting shoulders F⁴ to engage the frame, and means actuated by slides F for shifting the supplemental frame E backwardly and forwardly within the frame D.
15. In a typographical machine, the combination of the vertically movable frame D, the supplemental frame E supported therein and shiftable backwardly and forwardly therein and provided with the projecting studs E², the springs E¹ tending constantly to hold the frame E in its backward position, and mechanism for raising and lowering the frame D, said mechanism including the lifting slides F formed with the inclined surfaces F¹ to engage the studs E² and push the frame E forwardly against the action of its springs.
16. In a typographical machine, the combination of a plurality of superposed inclined magazines having their lower ends straight or right-angular, a channeled throat or switch shiftable in a straight vertical path from one magazine to another, and short channeled sections arranged at the delivery ends of the magazines so as to guide the matrices therefrom to the shiftable throat.
17. In a typographical machine, the combination of a magazine, a series of escapements therefor, a short channeled section arranged at the delivery end of the magazine, and a supporting frame carrying the escapements and channeled section, and movable at will out of operative relation to the magazine.
18. In a typographical machine, the combination of a magazine and its base frame, with a series of escapements for the magazine, a short channeled section arranged at the delivery end of the magazine, and a supporting frame carrying the escapements and channeled section and pivoted to the base frame so as to be movable at will out of operative relation to the magazine.
19. In a typographical machine, the combination of a plurality of magazines each pivotally mounted in the machine, and means for rocking the magazines simultaneously about their pivots, said means including cams to coöperate with the respective magazines, and the said cams being of different form to vary the extent of rocking of the magazines, for the purpose described.
20. In a typographical machine, the combination of a plurality of magazines, a pivoted supporting frame for each, and means for rocking the supporting frames simultaneously about their pivots, the said means including cams of different form to vary the extent of rocking of said frames.
21. In a typographical machine, the combination of a plurality of magazines, a pivoted supporting frame for each, and means for rocking the supporting frames simultaneously about their pivots, the said means including two pairs of cams of different form to coöperate with the respective supporting frames, a rock shaft whereon the cams are mounted, and an operating handle fast to the rock shaft.
22. In a typographical machine, the combination of the fixed machine frame, a plurality of superposed magazines pivotally connected to the fixed machine frame, and means whereby an upper magazine may be shifted upwardly away from an underlying magazine, for the purposes described.
23. In a typographical machine, the combination of a plurality of magazines, assem-

bling devices shiftable from one magazine to another, a pivoted supporting frame carrying the assembling devices and arranged to swing outward away from the 5 magazines, and mechanism for effecting the shifting of the assembling devices, said mechanism being mounted in part in the machine frame and in part in the pivoted frame and including connections which are automatically made and broken as the piv- 10 oted frame is swung to and from its operative position.

In testimony whereof, I have affixed my signature in presence of two witnesses.

DAVID S. KENNEDY.
